[57] CLAIM

The ornamental design of a housing for a telephone set,
as shown and described.

DESCRIPTION

FIG. 1 is a side elevational view of a housing for a telephone set, showing my new design in closed position, the opposite side being substantially a mirror image thereof;

FIG. 2 is a top plan view in closed position;

FIG. 3 is a bottom plan view in closed position;

FIG. 4 is an end elevational view in closed position, looking from the right in FIG. 1;

FIG. 5 is an end elevational view in closed position, looking from the left in FIG. 1;

FIG. 6 is a side elevational view in opened position, the opposite side being substantially a mirror image thereof;

FIG. 7 is a front elevational view in opened position; and

FIG. 8 is a rear elevational view in opened position.

FIG. 1
